DESIGN FOR AN ILLUMINABLE DISPLAY SIGN

Raymond M. Price, Chesterton, Ind., and Lewis E. Peters, Chicago, Ill.; said Peters assignor to said Price

Application November 23, 1946, Serial No. 135,926

Term of patent 14 years

(Cl. D1—12)

To all whom it may concern:

Be it known that we, Raymond M. Price and Lewis E. Peters, citizens of the United States, residing respectively in Chesterton, in the county of Porter and State of Indiana, and in Chicago, in the county of Cook and State of Illinois, are joint inventors for a new, original, and ornamental Design for an Illuminable Display Sign, of which the following is a specification, reference being had to the accompanying drawing, forming part thereof.

In the drawing:

We claim:

The ornamental design for an illuminable display sign, as shown.

RAYMOND M. PRICE.
LEWIS E. PETERS.
